UNITED STATES PATENT OFFICE.

WILHELM BECKER, OF NEW YORK, N. Y.

DESIGN FOR A WATCHCASE.

Application filed March 21, 1927. Serial No. 21,226. Term of patent 3½ years.

To all whom it may concern:

Be it known that I, WILHELM BECKER, a citizen of Germany, residing at New York, in the county of New York and State of New York, have invented a new, original, and ornamental Design for Watchcases, of which the following is a specification, reference being had to the accompanying drawing, forming part thereof.

I claim:

The ornamental design for a watchcase, as shown, and described.

WILHELM BECKER.
